(57) **CLAIM**

We claim the ornamental design for a tape lighting connection apparatus, as shown and described.

DESCRIPTION

FIG. 1 is a top perspective view of a tape lighting connection system.

FIG. 2 is a front elevation view of the tape lighting connection system of FIG. 1.

FIG. 3 is a rear elevation view of the tape lighting connection system of FIG. 1.

FIG. 4 is a top plan view of the tape lighting connection system of FIG. 1.

FIG. 5 is a bottom plan view of the tape lighting connection system of FIG. 1; and,

FIG. 6 is a left side elevation view of the tape lighting connection system of FIG. 1, the right side elevation view being a mirror image.

The broken lines represent portions of the tape lighting connection apparatus that form no part of the claimed design.
